(57) **CLAIM**

The ornamental design for a powder container, as shown and described.

DESCRIPTION

FIG. 1 is a front elevational view of a powder container;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof; and,
FIG. 7 is a rear, top, and left side perspective view thereof.
The broken lines in the drawings illustrate environmental subject matter and form no part of the claimed design.
